UNITED STATES PATENT OFFICE.

HERBERT J. ABRAMSON, OF ROCKFORD, ILLINOIS.

DESIGN FOR A SEWING-MACHINE TABLE.

SPECIFICATION forming part of Design No. 36,003, dated August 12, 1902.

Application filed June 23, 1902. Serial No. 112,845. Term of patent 3½ years.

To all whom it may concern:

Be it known that I, HERBERT J. ABRAMSON, a citizen of the United States of America, residing at Rockford, in the county of Winnebago and State of Illinois, have invented and produced a new, original, and ornamental Design for Sewing-Machine Tables; and I do hereby declare the following to be a full, clear, and exact description of the same, reference being had to the accompanying drawings, forming a part thereof.

In the drawings, Figure 1 is a perspective view, and Fig. 2 a rear elevation, of my new design for sewing-machine tables.

The sewing-machine table comprises the top A, having its front edge recessed and the end portions thereof formed in curves, as shown, the frame B, cover C, skeleton drawer-cases formed of the horizontal bottoms D, and vertical supports E, drawers F, having

their ends and outer sides curved to coincide substantially with the corresponding end portions of the top A and supported by the drawer-cases, formed of the parts D and E, and drawer G, extending between the two upper drawers and located beneath the top A, having its front ogee-curved in transverse section, as shown.

Having described my invention, what I claim as new, and desire to secure by Letters Patent, is—

The ornamental design for a sewing-machine table herein shown and described.

In testimony whereof I have signed my name to this specification in the presence of two subscribing witnesses.

HERBERT J. ABRAMSON.
